STEAM-ENGINE REVERSING-GEAR.

1,214,965.

Specification of Letters Patent.

Patented Feb. 6, 1917.

Application filed November 3, 1915. Serial No. 59,404

To all whom it may concern:

Be it known that I, JACOB RUSH SNYDER, a resident of Pittsburgh, in the county of Allegheny and State of Pennsylvania, have 5 invented a new and useful Improvement in Steam-Engine Reversing-Gear, of which the following is a specification.

This invention relates to mechanism for operating the reversing gear of steam engines, such as locomotives.

The object of the invention is to provide a fluid actuated device for moving the usual valve gear and which is so arranged that the valve gear actuating mechanism is free 15 to move whenever motive fluid is admitted thereto, but is positively locked at all other times, so as to not only prevent accidental movement of the valve gear after actuation but also prevent any kickback to the engineer or operator when setting the valve gear 20 reversing handle, and also one which is so arranged as to prevent the valve gear from being moved farther than intended, and to provide means for manually operating the 25 reversing gear should the power mechanism become inoperative from any cause.

The invention comprises the construction and arrangement of parts hereinafter described and claimed.

30 In the accompanying drawings, Figure 1 is a vertical sectional view through the actuating cylinder and the locking device for the reach rod and showing the valve mechanism for the operating cylinder and its actuating 35 means in elevation; Fig. 2 is an elevation of a portion of the actuating means shown in Fig. 1, showing the same on an enlarged scale; Fig. 3 is a vertical section on the line 3—3, Fig. 1, showing the valve mechanism 40 in outside view; Fig. 4 is a vertical section through the valve mechanism on an enlarged scale; Fig. 5 is a horizontal sectional view on the line 5—5, Fig. 2; Fig. 6 is a plan view of the reach rod locking device; Fig. 45 7 is a section thereof on the line 7—7, Fig. 6; Figs. 8, 9 and 10 are plan views respectively of the seat, the first or lower rotary disk, and the second or upper rotary disk of the valve mechanism; Figs. 9^a and 10^a are inverted plan views respectively of the rotary 50 disks shown in Figs. 9 and 10; Figs. 11, 12 and 13 are plan views looking down on the second or upper rotary disk and showing in dotted lines the various ports, passages and 55 cavities of both disks and of the valve seat

and showing the valve mechanism respectively in normal released and lock applying position, in lock applying position, and in cylinder application and lock releasing position; Fig. 14 is a plan view of the second 60 or upper rotary disk showing a modification; Figs. 15, 16 and 17 are diagrammatic views showing the different positions of the valve mechanism with this modification, and Fig. 18 is a sectional view on the line 18—18, 65 Fig. 10.

In the drawings, 1 represents a reversing cylinder in which works the piston 2 whose piston rod 3 is connected to the reversing or reach rod 4, which in turn is connected to 70 the usual reversing link mechanism of the engine, not shown. In neutral position the piston 2 stands midway of the length of the cylinder 1, and when it is moved in one direction, the link mechanism is moved to, say, 75 drive the engine forwardly, while, when the piston 2 is moved in the opposite direction, the link mechanism is moved to drive the engine backwardly. These movements of the piston are secured by admitting and exhausting 80 fluid pressure alternately to and from the opposite ends of the cylinder. A locking device is provided for preventing movement of the piston and rods connected thereto until the actuating means has been moved 85 fully to the desired position, to prevent the fluid pressure admitted to the cylinder from moving the actuating cylinder and injuring the engineer, and also locking said rods at all times except when fluid pressure is admitted 90 to said cylinder to move the reversing link mechanism, in order to prevent accidental movement of these parts after being set.

The rod locking device shown is in the form of a clamp embracing the reach rod 95 and comprises a stationary member 5 having pivotally connected thereto at 6 the gripping jaw 7 which is provided with an arm or extension 8 arranged to be actuated by a projection 9 on a movable abutment in the form 100 of a diaphragm 10 mounted in the small cylinder 11 and arranged to have motive fluid supplied to one face of said movable abutment in order to drive the projection 9 against the arm 8 and cause the jaw 7 to 105 grip the reach rod 4.

A special form of valve and actuating means therefor is provided for admitting pressure to and exhausting it from the opposite ends of the cylinder 1 and also ad- 110

mitting motive fluid to and exhausting it from the cylinder 11 of the locking device. This valve mechanism comprises a member 12 which is secured by means of nut 13 and key 13^a to the stationary segment 14, which is provided with a circular hub 15 on which are rotatably mounted an arm 16 and the valve actuating handle 17. The arm 16 has integral therewith a downwardly projecting arm 16^c which is provided at its lower end with a slotted fork 18 straddling the reach rod 4 and engaging a pin or anti-friction rollers 19 on said rod, so that the movement of the reach rod by the power cylinder 1 imparts movement to the arm 16, and vice versa.

Secured to the member 12 is a valve casting 21 closed at its outer end by the head 22 whose inner face forms a seat 23 of the valve. Working on this seat is the first or lower disk 24 whose opposite face in turn forms a seat for the top or second rotary disk 25. The rotary disks are held to the seat and against each other by a compression spring 26. The disk 24 is provided with a hollow stem which projects through the head 22 and has secured to its outer end an arm 28 which is secured to the actuating handle 17, so that the angular movement of the handle 17 carries with it the first or lower rotary disk 24. The inner or upper rotary disk 25 is also provided with a hollow stem which extends through the hollow stem of disk 24 and has secured to its outer end an arm 30 which has a slot and pin connection 31 with a bar 32 slidably mounted on the handle 17. To the lower end of the bar 32 is adjustably connected a plunger 33, such as by having the latter threaded on to the bar, as shown. The lower end of this plunger is square and engages a similar opening in a nut 34 having its periphery threaded and engaging the threaded interior of casing 35 secured to and forming a part of the arm 28 of handle 17, so that it at all times swings with said handle. In casing 35 are washers 36 and 36^a engaging respectively with shoulder 37 in the casing and the nut 34, and arranged in the downward and upward movements of the bar 32 to be engaged respectively by shoulders 38 and 38^a on said bar. Between the washers 36 is a compression spring 39, which acts to resist movement of the bar 32 either downwardly or upwardly, and therefore serves to move the bar back to neutral position irrespective of the direction in which it has been moved. By rotating the plunger 33, and with it the nut 34, the tension of the spring 39 can be adjusted. The upper end of bar 32 has a slot and pin connection 40 with a member 41 provided with a pair of hand grips 42 and 42^a lying respectively on opposite sides of the grip 43 of the handle 17, and which member 41 is pivoted to the handle at 44,

so that by moving either one of the grips 42 or 42^a toward the handle 43, the engineer can either elevate or depress the bar 32, as desired, depending upon the direction in which he wishes to move the main handle 17. 70

The handle 17 is held against accidental or unintentional movement in either direction by means of a pair of locking plungers 45 and 45^a which are slidably mounted in the handle 17, and are arranged to engage 75 on the opposite edges of the arm 16, and are held in engaging position with said arm by means of springs 46 interposed between said plungers and a bridge member 47 secured to the handle 17. Each of the plungers 45, 45^a is provided with a portion 48 overhanging the sliding bar 32, which is provided with a pair of oppositely arranged wedge-shaped or beveled projections 49—49^a, one above and the other below the locking-plungers 45, 45^a, and which wedges are adapted, when the bar 32 moves, to engage the overhanging portions 48 and retract the plungers 45, 45^a, to disengage the same from the arm 16. When, for instance, the hand grip 42 is grasped by the engineer together with grip 43, the bar 32 is depressed, thus bringing projection 49 underneath locking plunger 45 and retracting the latter so as to permit movement of the handle 17 toward the right (viewing Figs. 1 and 2), whereas, when the engineer grasps the hand grip 42^a together with grip 43, the bar 32 is lifted and causes the inclined projection 49^a to pass underneath the overhanging portion of plunger 45^a, thus retracting the same from engagement with arm 16, and permitting movement of handle 17 toward the left, (viewing Figs. 1 and 2). 90

The handle 17 is further locked against movement by means of a vertically slidable locking dog 50 provided at its lower end with a series of long teeth arranged to engage the long teeth 51 on the stationary segment 14. The dog 50 is provided at its upper end with a cross slot 52 in which moves a roller 53 carried by a downward extension 54 on the handle grip member 41, so that no matter in which direction this member 41 is rotated on its fulcrum 44 the locking dog 50 will be lifted and be disengaged from the rack bar 51 and permit the movement of handle 17 in either direction. 110

Mounted on handle 17 is a small cam 55, said cam being provided with a stem 56 extending through the handle 17 and receiving on its outer end a spring washer and nut 57, so that said cam, while free to rotate, is frictionally held so that it does not rotate freely or idly. On its lower face this cam is provided with a notch 58 arranged to be normally engaged by a finger 59 on the upper end of the arm 16. The upper face of the cam normally projects above the bottoms of the teeth 51 of segment 14, and 120

125 130

is provided with a number of notches which the teeth on the lower end of locking dog 50 can enter so as to permit said locking dog to fall fully downward.

5 The valve casing 21 is provided with an inlet 60 for motive fluid to the space above the rotary disks in said casing, and the valve seat 23 is provided with three ports, to wit, port 61 connected by pipe 62 to one end of the cylinder 1, port 63 connected by pipe 64 to the opposite end of cylinder 1, and port 65 connected by pipe 66 to port 67 of the lock actuating cylinder 11.

10 The lower rotary disks 24 is provided with three ports, marked 68, 69 and 70 respectively, which extend entirely through the disk, and which communicate with grooves on the lower face of said disk, which grooves are of such length that communication between the ports in the valve seat and the ports through said disk is not broken by the rotation of the disk 24 to the extent permitted by the actuating connections.

15 25 In order to reduce friction the lower face of the top disk 25 is cut away in part so as to leave raised portions or projections which alone contact with the valve seat and control the ports in the lower disk. As shown, 30 said disk 25 has an arc-shaped raised portion or projection 71 provided with a pair of circular ports 72 each connected by a radial passage 73 with a hollow 74 in the stem of said valve, which hollow 74 forms 35 the exhaust, said projection 71 being intercepted by a radial groove 82; and a pair of arc-shaped raised portions or projections 75 and 76 provided respectively with arc-shaped cavities 77 and 78 connected by radial passages 79 with the hollow 74 of the 40 stem of said valve, and which projections 75 and 76 are intercepted respectively by radial grooves 80 and 81.

45 Normally the handle 17 is in the position shown in Figs. 1 and 2, being held between the locking plungers 45—45^a on each side thereof, and with the locking dog 50 engaging the teeth 51 of segment 14 and also the notches in the upper face of cam 55. In this 50 position the piston 2 is midway of the length of the cylinder 1 and the valve mechanism is in the position shown in Fig. 11 in which the ports 68, 69 and 70 of the first rotary disk register with the ports 61, 63 and 65 in 55 the valve seat, cavities 77 and 78 of the second disk register respectively with ports 68 and 69 and thus connect both ends of the cylinder 1 through radial passages 79 with the exhaust passage 74; while the radial 60 groove 82 intercepting the raised portion of projection 71 permits motive fluid to pass to port 70 and thence to port 65, connected to the cylinder 11 of the reach rod locking device. Consequently in this position both 65 ends of the power cylinder 1 are exhausted,

but the reach rod is locked so that accidental movement of the reversing link mechanism cannot occur.

To shift the valve gear, the engineer moves one of the hand grips 42 or 42^a, depending upon the direction in which he wishes to shift the handle 17. When he wishes to shift said handle toward the right, Fig. 1, he grasps the grips 42 and 43, thus depressing the bar 32, and retracting locking plunger 45, whereas, if he wishes to shift the handle 17 to the left, he grasps the grips 42^a and 43, thus lifting the bar 32 and retracting the locking plunger 45^a. In the former case the valve gear will be shifted to 70 drive the engine say forward, and in the latter case to reverse the engine. Assuming that the engineer wishes to drive the engine forwardly, he will grasp the hand grips 42 and 43, rotating the member 41 75 about its fulcrum 44 and depressing bar 32, thereby causing the inclined projection 49 to retract the locking plunger 45, and permit movement of the handle 17 to the right.

At the same time the roller 53 working in 80 the cross groove 52 of the dog 50 lifts the latter to disengage it from both the cam 55 and the stationary rack teeth 51. The downward movement of bar 32, through the arm 31 also rotates the top disk 25 to the position shown in Fig. 12, but without moving 85 the bottom disk. This movement produces no change whatsoever in the relation of cavity 78 and ports 69 and 63, so that the left hand end of cylinder 1 is still open to 90 exhaust, but results in blanking port 68 by the solid part of projection 75 on the top-most disk, while port 70 is in this position also uncovered (the projection 71 having 95 passed entirely beyond the same), so that 100 motive fluid is still flowing to the reach rod locking cylinder 11. As a consequence, the reach rod is held against movement while 105 the engineer moves the handle 17, so that 110 there can be no kickback from the valve gear to said handle 17 which would be likely to injure the engineer. The engineer now moves the handle 17 to the right to any desired distance. Said lever in its movement carries with it the bar 32, and also the lower 115 disk 24. Consequently both of the rotary disks 24 and 25 are moved through the same arc as the handle 17, but without producing any change in their relative relations. The 120 arc-shaped slots of the lower face of the disk 24 are of such length that such movement of the disk through the extreme distance through which handle 17 can move the same will not break connection with the 125 ports 61, 63 and 65 of the valve seat, so that during this movement the relations shown in Fig. 12 are in no manner disturbed.

130 The handle 17 is moved it carries with cam 55, and inasmuch as the arm 16 finger 59 are stationary, the engagement of 135

the latter with notch 58 in the cam causes the latter to be rotated clockwise, so that the notches in its upper face are brought to such position that when the handle is released, the locking dog 50 will not drop fully 5 downwardly, but only until its teeth engage with the unnotched periphery of cam 55. Consequently as soon as the engineer releases the handle after having moved it to the desired position, the locking dog 50 will fall part-way down only, causing a corresponding upward movement of the bar 32, and rotating the upper disk 25 backwardly about one-half of the distance of its original 10 movement when the bar 32 was lowered. This brings the valves to the position shown in Fig. 13, in which the ports 68, 69 and 70 are still in register with the ports 61, 63 and 65 in the valve seat, while port 72 of 15 the upper rotary disk registers with port 70, thus permitting the reach rod cylinder 11 to exhaust through ports 65, 70, 72 and radial passages 73 to exhaust passage 74; cavity 78 still registers with port 69, so that 20 the left hand end of cylinder 1 is still open to exhaust, but radial groove 80 through the projection 75 now uncovers port 68, thus permitting motive fluid to flow to the right hand end of cylinder 1 and move the piston 25 2 and reach rod 4 to shift the reversing link mechanism. The movement of reach rod 4 through the connection 19 and arm 16^a now swings the arm 16 in the same direction in which the handle 17 was moved. This movement will continue until the finger 59 on the 30 arm 16 engages notch 58 in cam 55 and rotates the latter contra-clockwise until the notches in its upper surface are brought into line with the teeth on the locking dog 50, whereupon the latter immediately drops down into said notches, permitting the bar 32 to rotate the top rotary disk 25 backwardly to its original position relative to the disk 24, thus reestablishing the same relations as shown in Fig. 11, the only difference being that both disks have been rotated 35 around contra-clockwise, but without disturbing their relative relations from that shown in Fig. 11 or breaking the connection between the arc-shaped slots on the lower 40 face of disk 24 and the ports in the valve seat. In this position the top disk again establishes communication between port 68 and the exhaust port 74, so that both ends 45 of cylinder 1 are again exhausted; while at the same time the radial groove 82 again permits motive fluid to flow to port 70 and thence to port 65 and to the reach rod locking cylinder 11. 50 When it is intended to reverse the engine, the handle 17 is merely moved in the opposite direction from that described, to wit, toward the left, and the valve disks are then 55 both rotated in the opposite directions from those described, but produce exactly the same

results as described, except only that in this case the motive fluid is admitted to the left hand end of cylinder 1, and causes movement of the reach rod in the opposite direction from that described. 70

The valve mechanism described is therefore so organized that the reach rod is locked at all times (including the time of movement of handle 17) except during the interval of time immediately after the handle has reached its final position and the locking dog 50 has dropped half way down, at which time motive fluid is admitted to one or the other end of cylinder 1 and the reach rod locking cylinder 11 is exhausted so as to 80 permit movement of the reach rod and link mechanism. As soon, however, as the reach rod has moved to the desired position and the finger 59 has turned the cam 55 so as to allow the locking dog to fall down fully, 85 motive fluid is exhausted from the cylinder 1, and the reach rod is again locked, and remains locked until the handle 17 is again shifted. Consequently the reversing link mechanism can not be accidentally jarred 90 out of the position to which set, and at the same time the reach rod is locked so that there can be no kickback during the time that the engineer is moving the handle 17. 95

The valve mechanism described insures 100 the movement of the valve gear positively and to the desired extent and requires no attention of the engineer other than to unlock the handle 17 by either lifting or depressing the bar 32, and then move the handle to the desired position, all of the other operations taking place entirely automatically. The engineer cannot move the handle 17 except in the direction of the particular locking plunger 45 or 45^a which has been retracted. 105

In case the power mechanism becomes inoperative from any cause, it is only necessary to disconnect the bar 32 from handle 17, by removing pin 40, and then shift the 110 reversing gears by handle 17, which can be done because the upper end of arm 16 is held between the plungers 45, 45^a, on handle 17 and must therefore move with said handle, while its extension 16^a connects directly 115 to the reach rod 4.

Figs. 14, 15, 16 and 17 show a modification of the valve mechanism, in which the portions of the projections 75 and 76 which are cut off by the radial grooves 80 and 81 have 120 been entirely omitted. The only effect of this modification is that when the bar 32 is either lifted or depressed and the handle 17 free to be moved, the port 68 (or the port 69, depending on the direction in which the handle 17 is moved) is uncovered, as shown in Fig. 16, and is not blanked as shown in Fig. 12 in the preferred modification. As a result motive fluid immediately flows to the 125 cylinder 1, instead of being prevented from 130

flowing thereto until the handle has been moved fully to the desired position and released so as to permit the dog 50 to drop part way down, as in the preferred modification. Inasmuch, however, as the reach rod is still locked during this time, the admission of fluid pressure to the power cylinder during the time that the handle 17 is being moved, produces no result as the cylinder has considerable capacity and there is little danger of getting a high pressure therein during the time that it takes to move the handle 17 to the desired position. In all other respects this modification operates identically the same as the preferred form.

What I claim is:—

1. In valve reversing mechanism, the combination of a reversing fluid pressure motor, a reversing rod actuated thereby, a fluid pressure actuated locking device for said rod, and valve mechanism controlling the supply and exhaust of motive fluid to and from the two sides of said motor and to and from said locking device and arranged while setting said valve mechanism to the desired position to maintain fluid pressure in said locking device and exhaust it from said motor, and when said valve mechanism has been set to the desired position to exhaust the motive fluid from said locking device and admit motive fluid to one side of said motor.

2. In valve reversing mechanism, the combination of a reversing fluid pressure motor, a reversing rod actuated thereby, a fluid pressure actuated locking device for said rod, valve mechanism controlling the supply and exhaust of motive fluid to and from the two sides of said motor and to and from said locking device and arranged to admit motive fluid to the locking device when setting the valve mechanism to the desired position, to exhaust motive fluid from said locking device and simultaneously admit motive fluid to one side of the motor when the valve mechanism has been set in the desired position, and means actuated by the travel of the reversing rod for causing said valve mechanism when the rod has traveled the required distance to exhaust said motor and simultaneously admit motive fluid to said locking device.

3. In valve reversing mechanism, the combination of a reversing fluid pressure motor, a reversing rod actuated thereby, a fluid pressure actuated locking device for said rod, an actuating handle, valve mechanism controlling the supply and exhaust of motive fluid to and from the two sides of said motor and to and from said locking device and arranged to admit motive fluid to said locking device upon movement of said handle, to release motive fluid from said locking device and simultaneously admit motive fluid to the motor to move said rod upon

movement of the handle to the desired position, and after movement of said rod to the desired extent to again admit motive fluid to the locking device and simultaneously exhaust it from said motor.

4. In valve reversing mechanism, the combination of a reversing fluid pressure motor, a reversing rod actuated thereby, an actuating handle, a fluid pressure actuated locking device for said rod, valve mechanism controlling the supply and exhaust of motive fluid to and from the two sides of said motor and to and from said locking device and arranged upon movement of said handle to admit motive fluid to the locking device, and when the handle has been moved to the desired position to release motive fluid from said locking device and simultaneously admit motive fluid to the motor to move the rod, and means actuated by the travel of said reversing rod for causing said valve mechanism when the rod has traveled the required distance to exhaust said motor and simultaneously admit motive fluid to said locking device.

5. In valve reversing mechanism, the combination of a reversing fluid pressure motor, a reversing rod actuated thereby, an actuating handle, a locking member for said handle, a fluid pressure actuated locking device for said rod, and valve mechanism controlling the supply and exhaust of motive fluid to and from the two sides of said motor and to and from said locking device and arranged when the handle locking member is actuated to release the handle to admit motive fluid to the rod locking device, upon movement of said handle to the desired position to exhaust motive fluid from the rod locking device and simultaneously admit it to the actuating motor, and upon movement of the handle locking member to again lock the handle to exhaust motive fluid from the motor and simultaneously admit it to the rod locking device.

6. In valve reversing mechanism, the combination of a reversing fluid pressure motor, a reversing rod actuated thereby, an actuating handle, a locking member for said actuating handle, a fluid pressure actuated locking device for said rod, valve mechanism controlling the supply and exhaust of motive fluid to and from the two sides of said motor and to and from said rod locking device and arranged upon movement of said handle locking member to release said handle to admit motive fluid to said rod locking device, and upon movement of the handle to the desired position to exhaust motive fluid from the rod locking device and admit motive fluid to one side of the motor, and means actuated by the travel of said reversing rod when it has traveled to the required distance to permit the handle locking member to again lock the handle and

simultaneously move the valve mechanism to exhaust motive fluid from the motor and simultaneously admit motive fluid to the rod locking device.

- 5 7. In valve reversing mechanism, the combination of a reversing fluid pressure motor, a reversing rod actuated thereby, a fluid pressure actuated locking device for said rod, valve mechanism controlling the supply and exhaust of motive fluid to and from the two sides of said motor and to and from the said locking device, an actuating handle for said valve mechanism, a lock for said handle, means arranged upon the releasing 10 of said handle lock to simultaneously actuate said valve mechanism and admit motive fluid to the rod locking device, and means when the handle has been moved to the desired position to permit the partial restoration 15 of said handle lock and thereby move the valve mechanism to exhaust motive fluid from the locking device and simultaneously admit motive fluid to the motor.
8. In valve reversing mechanism, the combination of a reversing fluid pressure motor, a reversing rod actuated thereby, a fluid pressure actuated locking device for said rod, valve mechanism controlling the supply and exhaust of motive fluid to and from the two sides of said motor and to and from the said locking device, an actuating handle for said valve mechanism, a lock for said handle, means arranged upon the releasing 20 of said handle lock to simultaneously actuate said valve mechanism and admit motive fluid to the rod locking device, means when the handle has been moved to the desired position to permit the partial restoration of said handle lock and thereby move the valve 25 mechanism to exhaust motive fluid from the locking device and simultaneously admit motive fluid to the motor, and means actuated by the travel of the reversing rod when it has traveled the required distance to permit the full restoration of the handle locking member and thereby move the valve mechanism to again admit motive fluid to the rod locking device and exhaust motive fluid from the motor.
- 50 9. In valve reversing mechanism, the combination of a reversing fluid pressure motor, a reversing rod actuated thereby, a fluid pressure actuated locking device for said rod, valve mechanism controlling the supply and exhaust of motive fluid to and from the two sides of said motor and to and from the said locking device, an actuating handle for said valve mechanism, a locking member for said handle, and connections therefrom to said valve mechanism so arranged that when said handle locking member locks the handle in position motive fluid is admitted to the rod locking device and exhausted from the motor, upon movement of said handle locking member to release said

70 handle the valve mechanism maintains motive fluid to said rod locking device, upon movement of the handle to the desired position the valve mechanism is moved to exhaust motive fluid from the rod locking device and admit it to the motor, and upon movement of the handle locking member to re-lock said handle motive fluid is released from said motor and re-admitted to said rod locking device. 75

10. In valve reversing mechanism, the combination of a reversing fluid pressure motor, a reversing rod actuated thereby, a fluid pressure actuated locking device for said rod, valve mechanism controlling the supply and exhaust of motive fluid to and from the two sides of said motor and to and from the said locking device, an actuating handle for said valve mechanism, a locking member for said handle, connections therefrom to said valve mechanism so arranged that when said handle locking member locks said handle motive fluid is admitted to said rod locking device and exhausted from said motor, upon movement of said handle locking device to release said handle said valve mechanism maintains motive fluid in said rod locking device, upon movement of said handle to its desired position said valve mechanism is moved to exhaust the motive fluid from said rod locking device and admit motive fluid to said motor, and means actuated by the travel of the reversing rod when it has traveled to the required distance for permitting movement of the handle locking member to again lock the handle and thereby move the valve mechanism to exhaust motive fluid from the motor and admit motive fluid to the rod locking device. 90 95

11. In valve reversing mechanism, the combination of a reversing fluid pressure motor, a reversing rod actuated thereby, a fluid pressure actuated locking device for said rod, valve mechanism controlling the supply and exhaust of motive fluid to and from the two sides of said motor and to and from the said locking device, an actuating handle for said valve mechanism, a locking member for said handle, connections from said locking member to the valve mechanism 100 and arranged when the handle locking member locks the handle in position to admit motive fluid to the rod locking device and exhaust it from said motor, upon movement of said handle locking member to unlock the handle to move the valve mechanism to maintain fluid pressure in the rod locking device, means actuated by the movement of said handle to prevent full restoration of said handle locking member, whereupon upon movement of the handle to the desired position the partial restoration of the handle locking member causes movement of the valve mechanism to exhaust fluid pressure from the rod locking device and admit fluid 105 110 115 120 125

- pressure to the motor, and means actuated by the travel of the reversing rod when it has traveled to the required distance and actuating the aforesaid means to permit the 5 full restoration of the handle locking member and thereby cause movement of the valve mechanism to again admit motive fluid to the rod locking device and exhaust motive fluid from the motor.
- 10 12. In valve reversing mechanism, the combination of a reversing fluid pressure motor, a reversing rod actuated thereby, a fluid pressure actuated locking device for said rod, valve mechanism controlling the 15 supply and exhaust of motive fluid to and from the two sides of said motor and to and from the said locking device, an actuating handle for said valve mechanism, a locking dog for said handle, connections from the 20 same to said valve mechanism, a member carried by said handle and controlling the position of said locking dog, and means movable with the reversing rod and engaging said dog controlling means and arranged 25 upon movement of the handle to move said latter means to prevent full restoration of said locking dog, and upon movement of the reversing rod to the required distance, to again engage said means and move the 30 same to permit full restoration of said locking dog.
13. In valve reversing mechanism, the combination of a reversing fluid pressure motor, a reversing rod actuated thereby, a fluid pressure actuated locking device for 35
- said rod, valve mechanism controlling the supply and exhaust of motive fluid to and from the two sides of said motor and to and from the said locking device, an actuating handle for said valve mechanism, connections 40 between the handle and said reversing rod arranged to be disconnected when the valve mechanism is operated, and detachable connections between the handle and the valve mechanism. 45
14. In valve reversing mechanism, the combination of a reversing fluid pressure motor, a reversing rod actuated thereby, a fluid pressure actuated locking device for said rod, valve mechanism controlling the 50 supply and exhaust of motive fluid to and from the two sides of said motor and to and from the said locking device, an actuating handle for said valve mechanism, an arm connected to said reversing rod, a lock arranged to normally connect said arm to said handle, connections between said handle and said valve mechanism arranged when moved to actuate said valve mechanism to release said lock and disconnect said arm from said 55 handle, and a separable means in the connection between said handle and the valve mechanism. 60

In testimony whereof, I have hereunto set my hand.

JACOB RUSH SNYDER.
